LEWIS B. DOMAN, OF ELBRIDGE, NEW YORK, ASSIGNOR TO AMPHION PIANO PLAYER COMPANY, OF ELBRIDGE, NEW YORK, A CORPORATION OF NEW YORK.

SELF-PLAYING MUSICAL INSTRUMENT.

1,075,313.

Specification of Letters Patent.

Patented Oct. 7, 1913.

Application filed August 22, 1904. Serial No. 221,995.

To all whom it may concern:

Be it known that I, LEWIS B. DOMAN, of Elbridge, in the county of Onondaga, in the State of New York, have invented new and useful Improvements in Self-Playing Musical Instruments, of which the following, taken in connection with the accompanying drawings, is a full, clear, and exact description.

10 This invention relates to certain improvements in self-playing musical instruments, referring more particularly to the expression controlling and allied mechanisms, somewhat similar to my reissue application 15 No. 594,228 filed November 25, 1910, and also to my pending applications Nos. 240,252 filed March 9, 1905, and 329,692 filed August 8, 1906. In this class of instruments a series of primary and key operating pneu- 20 matics are placed in communication with a suitable air-pump or bellows and tracker-board over which a perforated music-sheet is caused to travel to control the action of said pneumatics for operating the keys or 25 hammers of a piano or other key-board instrument.

The primary object of my present invention is to enable the operator to easily grade at will the expression or force of action of 30 the keys of the instrument to either extreme or to any intermediate degree by simply varying the degree of air pressure which operates the primary and key striking pneumatics without changing the pressure in the 35 main bellows.

A further object is to provide means operable by a light pressure of the finger for accenting an individual note or chord when the general expression of the selection, or 40 any portion of it, is below or softer than "fortissimo" and without shifting the expression controlling lever so that if the lever is set for "pianissimo" or any intermediate degree of expression any individual note or chord may be accented with full 45 fortissimo expression the instant the corresponding perforation in the music sheet is registered with its duct in the tracker-board, without changing the position of the hand 50 or the expression lever.

Other objects and uses will be brought out in the following description.

In the drawings—Figure 1 is an end view partly in section of a portion of a pneumatic piano player embodying the essential features of my invention. Fig. 2 is a front view, partly in section, of parts of the mechanism seen in Fig. 1, showing the particular features of novelty together with the tempo controlling lever. Fig. 3 is a top plan of the main exhaust chambers and expression controlling pneumatics. Fig. 4 is a front elevation of the expression controlling pneumatics. Fig. 5 is a sectional view of the expression controlling lever and means for accenting individual notes and chords. Fig. 6 is a detail view of a modified means for accenting individual notes or chords.

The apparatus shown comprises essentially a key action, an expression controlling mechanism including a device for accenting individual chords, and suitable exhausting means operating to maintain a partial vacuum in portions of the key action and expression controlling mechanism.

The key-action is similar to that set forth in my pending applications Serial Nos. 227470 and 227471, filed Oct. 6, 1904 for operating the keys, as —1—, of a piano or other key-board instrument, and consists essentially of a series of key-operating pneumatics —2—, one for each key of the piano, which are connected to and operate suitable key-striking fingers —3—, and communicate with corresponding primary pneumatics —4— through a port —5—, and also communicate with atmosphere through suitable ports —6—. Each primary pneumatic is provided with a valve —7— which plays 90 between the ports —5— and —6— to alternately connect the key-striking pneumatics with an exhaust chamber —8— and atmosphere.

The exhaust chamber —8— is common to 95 and at one side of all of the primary pneumatics 4, but the space at the opposite side of each primary pneumatic is connected by separate air conduits, as —9—, to one of a series of tracker-board ducts —10— across 100

which the perforated music sheet —11— travels and controls the operation of the primary pneumatics and their corresponding key striking pneumatics.

5 The conduits —9— are provided with comparatively small apertures —12— which open into an exhaust chamber —13—, and this exhaust chamber —13—, together with the exhaust chamber —8— of each wind-chest of the key action is connected to a conduit 14— which is in communication with the exhaust device so that a partial vacuum is maintained in these chambers —8— and —13— below atmospheric pressure when the ducts —10— are closed by the music-sheet, but as soon as one or more perforations in the music-sheet are registered with the corresponding ducts in the tracker-board the air at atmospheric pressure enters 10 beneath the primary pneumatics and by reason of the lower pressure in the chamber —8— causes said primary pneumatic to operate the valve —7— to establish communication between the key striking pneumatic and chamber —8— and to cut off communication between said key pneumatic and atmosphere, thereby causing the sudden collapse of the key striking pneumatic to operate the corresponding key of the musical instrument. I have only briefly described this key action for the reason that it is fully set forth in my pending applications above referred to, and forms no part of my present invention, except as it enters 15 into combination with the expression controlling mechanism presently described. In this expression controlling mechanism, I employ two separate exhaust chambers —15— and —16—, one of which, as —15—, is connected by a conduit —17— to a suitable air exhausting bellows or equalizer —18—, only a portion of which is shown in Fig. 1, as the means for maintaining the partial vacuum in the chamber 15— forms no part 20 of my present invention, and may be of any desired construction. The chamber 15— communicates through a port —19— with the interior of a pressure regulating pneumatic —20— in which is located a second, but somewhat smaller pneumatic 21. The chamber —16— also communicates with the interior of the pneumatic —20— through a port —22— and is connected by a conduit —23— to the conduit —14— shown by dotted lines in Fig. 1, and is therefore, in communication with the chamber —8— of the key-action. It is now apparent that the chamber —16— is also in communication with the exhaust device —18— by reason of 25 the fact that both ports —19— and —22— open into the interior of the pneumatic —20— and since the chamber —16— is in communication with the exhaust device and also in communication with the chambers —8— and 13— it is evident that these latter 30 chambers are also in communication with the exhaust device.

The pneumatic —20— is preferably made in the form of a bellows, as seen in Fig. 2, and therefore, has a movable wall which is 70 normally distended by means of a spring —24—, and this spring is tensioned so as to give the desired pressure available in the key action pneumatics, or rather determines the pressure available in the chambers —8— 75 and 13—. The small pneumatic —21— is also preferably made in the form of a bellows mounted upon the movable wall of the bellows —20— and has, itself, a movable wall —25— to which is secured a somewhat 80 spongy or porous valve —26—, which in this instance is made of coarse felt and is adapted to cover the port —19— to regulate the passage of air from the interior of the bellows —20— to the chamber —15— 85 These pneumatics —20— and —21— are very similar in construction and operation to that set forth in my pending application previously referred to with the exception that the valve —26— is made of coarse felt 90 or other finely porous material, and it is therefore, unnecessary to further illustrate or describe this part of the apparatus further than to state that the object of the porous or felt valve —26— is to permit the 95 air to sift therethrough when it is closed in order to subdue the force or pressure of the air without entirely cutting off communication between the pneumatic —20— and chamber 15—. This enables me to obtain 100 extremely soft degrees of expression and avoids the quick positive cut-off, such as would be produced by a leather or equivalent valve, and also produces easy "glides" 105 or gradations of expression owing to its porosity and susceptibility to gradual compression under varying degrees of pressure. Reference is here made to my pending application No. 249,250 filed March 9, 1905, as showing similar expression graduating 110 pneumatics.

It now appears that a substantially uniform air pressure below atmosphere is maintained in the chamber —15— by reason of its direct connection with the exhaust 115 device 18— and that the pneumatic —20— and felt valve —26—, together with the spring —24—, constitutes what may be termed, a maximum pressure regulator for determining the pressure available in the 120 key-action, or rather, in the chambers —8— and 13— so that such maximum pressure in the key-action may be equal to or less than the pressure in the exhaust device or in the chamber —15— depending upon the tension 125 of the spring —24—. For example—if the force of the suction of the exhaust device exceeds the tension of the spring —24— the pneumatic —20— will be partially collapsed sufficiently to cause the valve —26— to par- 130

tially close the port —19— until limited by a stop —27— of the pneumatic —20—, which together with the porosity of the valve 26— prevents absolute closure of the port —19—.

5 The bellows —21— constitutes what may be termed, the accenting pneumatic, that is, it performs the function of unseating the valve —26— in a manner hereinafter described for accenting an individual note or chord when the pressure in the key-action is set to produce a degree of expression softer than fortissimo *f*. The gradation of expression from pianissimo through intermediate degrees to fortissimo is controlled by a plurality of—in this instance four, separate pneumatics —28—, each of which is of substantially the same capacity and all combined have a capacity or area substantially 10 equal to the capacity or area of the bellows or pressure regulating pneumatic —20— and are arranged with their movable walls facing the movable wall of the pneumatic —20—.

25 The movable wall of each of the pneumatics —28— is connected by a separate connection, as a link —29—, to the movable wall of the pneumatic —20— and the interior chamber of each of the pneumatics 30 —28— is connected by a conduit —30— to an air cylinder or chamber —31—, which in turn, is connected by a conduit —32— to the chamber —15— so that these pneumatics —28— are in direct connection with the 35 exhaust device through the conduits —30—, chamber —31—, conduit —32—, chamber —15— and conduit —17—.

A piston —33— is movable in the cylinder —31— across the mouths of the conduits 40 —30— for the purpose of cutting off communication between one or more of the conduits —30— and chamber —15— so that when the piston is drawn back to uncover the mouths of all of the conduits —30— the 45 combined pressure in all of the pneumatics —28— is substantially equal to the pressure in the pneumatic —20—, when the valve —26— is fully opened and therefore, the action of the exhaust device upon the bellows —20— is neutralized and permits the 50 action of the exhaust device with full force upon the key action to produce the extremely loud or "fortissimo" expression in the selection which is being played. On the 55 other hand—if the piston is moved to the extreme inner position for cutting off communication between all of the pneumatics —28— and chamber —15— the full force of atmospheric pressure is exerted upon the bellows —20— proportionate to the degree 60 of the vacuum in the chamber —15— which operates to partially close the valve —26—, thereby allowing the air to strain or sift through the somewhat porous felt valve to 65 produce an extremely soft or, "pianissimo"

effect in the selection which is being rendered. It is now clearly evident that by moving the piston —33— to intermediate points so as to cut off one or more of the conduits —30— from communication with the chamber —15— a degree of pressure is exerted upon the bellows —20— proportionate to the excess of area or capacity of the pneumatic —20— over the area or capacity of the pneumatics —28— which may be in action or communication with the chamber —15—. For example—suppose that the piston or valve —33— is set, as shown in Fig. 2, so as to cut out two of the conduits —30— leaving the remaining two conduits —30— 70 in communication with the chamber —15—, then the force of the exhaust device operating to collapse the bellows —20— is counteracted by substantially half the same force acting upon the pneumatics —28— which remain in communication with the chamber —15—, and therefore, the felt valve —26— is closed only under a medium pressure, which produces a corresponding air pressure in the key-action and gives an intermediate expression in the selection represented by *m*, *f*, or *mezzo-forte*. In like manner, by moving the piston backward and forward the expression may be changed from one extreme to the other, or to any intermediate 90 degree depending upon the number of pneumatics —28— which may be employed. Although I have shown only four of these pneumatics —28— it is evident that any number may be used, but the combined area 95 or capacity of these governing pneumatics must be substantially equal to the area or capacity of the pressure regulating pneumatic —20—.

The means employed for controlling the 105 operation of the piston —33— preferably consists of a lever —34— which is fulcrumed at —35— and has its lower end connected by a link —36— to the piston —33— and its upper end is arranged in a position convenient for operation and is provided with an index finger —37— which is movable along a suitable scale or index —38— having different characters, such as *f*, *f*, *mf*, *p*, and *pp*, representing fortissimo, pianissimo and 110 intermediate degrees of expression. It is evident, however, that various other means may be employed for making and breaking connection between the pneumatics —28— and chamber —15—, as for instance, this 115 may be accomplished automatically by making suitable apertures in the music-sheet to coöperate with extra ducts in the tracker-board which might be connected to control separate valves for closing the mouths of 120 the ducts —30—, or these extra ducts in the tracker-board might be connected by separate ducts to admit air under atmospheric pressure into said pneumatics —28—.

125 The means for accenting individual notes 130

or chords during the rendition of the selection comprises essentially the pneumatic —21— which is connected by a conduit —40— to a chamber —41— which has a port —42— opening to atmosphere and another port —43— which communicates with a second chamber —44—. This latter chamber —44— is connected by a conduit —45— to the exhaust chamber —15—, and is therefore, in direct communication with the exhaust device. A valve —46— plays in the chamber —41— between the ports —42— and —43— and normally closes the port —43—. This valve has a stem extending through the port —43—, and just beneath this stem is a pneumatic or diaphragm —47— which plays in the pocket —48— and has a small aperture —49— connecting the chamber —44— with the pocket —48— so that the pocket —48— is also in communication with the chamber 15—. Leading from this pocket is a tube or air conduit —50— which has diverging branches —51— and —52—, one of which opens into an air chamber —53— having a port —54— and a spring closed valve —55— for closing said port which otherwise opens to atmosphere. This chamber 53 is formed in a comparatively small inclosure which is mounted upon the lever —34—. This lever —34— is provided with a lengthwise guide —56— in which is movable a plunger rod —57— having its upper end projecting slightly above the upper end of the lever and its lower end is guided in an opening —58— at one side of the chamber —53— and engages the valve —55— which is normally closed by a spring 59 so that by placing the finger upon the upper end of the plunger-rod —57— it may be easily and quickly depressed and released to open the valve —55— to admit air under atmospheric pressure through the port —54— and into the conduit —51— and beneath the pneumatic —47—. This causes an instantaneous action of the diaphragm —47—, which operates the valve —46— to close the port —42— and to open communication between the chamber —44— and conduit —40—, and therefore, to establish communication between the interior of the pneumatic —21— and chamber 15—, thereby throwing the full force of the vacuum of the chamber 15— into the pneumatic —21— and causing said pneumatic —21— to collapse and open the valve —26—. The instant this is accomplished it is apparent that the full force of the exhaust device is thrown to the key action, and therefore operates the keys with full fortissimo effect. This individual note and chord accenting device is a particularly important feature of my invention in view of the fact that the plunger rod, or as it may be termed, the accenting button—may be operated by the finger while the hand is still

upon the expression controlling lever —34— without in any way changing the position of the hand or lever. A similar accenting device may be connected to one or more of the other levers, such for instance—as a tempo controlling lever —60— which carries an air chamber —53— connected to the branch —52— and also carries an accenting button or rod —57— for operating the valve —55—, these mechanisms being identical with those described as being mounted upon the lever —34— and it is evident that I may, if desired, equip the pedal operating levers with the same kind of an accenting device.

In some instances it may be desirable to operate the accenting device automatically, as for instance, by extra perforations in the music-sheet moving across corresponding ducts in the tracker-board which may be connected to the conduit —50— whereby the air under atmospheric pressure would be admitted into the pocket —48—, or instead of connecting the duct as described, it might be connected to an extra duct in the tracker-board to operate with one or more extra perforations in the music-sheet to automatically control the accentuation of the individual notes or chords, and in Fig. 6, I have shown a tracker-board having an extra duct —a— which is connected by a conduit —b— to the conduit —50— and communication with the atmosphere is controlled by extra perforations, as —c— in the music-sheet, as —C—, so that the accenting of the individual notes or chords may be effected automatically or manually.

In the operation of my invention a partial vacuum is maintained in the chamber —15—, and also in the chambers —31— and —44— at a pressure below atmosphere substantially equal to the pressure in the exhaust device and when the ports of the conduits —30— opening into the chamber 31— are all uncovered and the valve 26 is fully opened a similar pressure below atmosphere is maintained in the bellows —20— and governing pneumatics —28— and these pneumatics —20— and —28— being linked to each other and of substantially the same area, it is evident that the pressure upon the bellows 20 is neutralized by the equal pressure in the combined pneumatics —28—, and therefore, the full force of the exhaust device is transmitted to the key action for producing fortissimo effect in the rendition of the selection. Now, when it is desired to soften the expression it may be done step-by-step by moving the piston —33— to cover one or more of the ports of the conduits —30—, thereby cutting off the corresponding pneumatics —28— from communication with the exhaust device, thus breaking the neutralizing effect of the pressure upon the pneumatic —20—, whereupon said

pneumatic —20— is partially collapsed against the tension of the spring —24— to partially cut off communication between the exhaust device and key action, thereby sub-
5 ding the force of action of the key pneumatics and permitting the operator to control the expression step-by-step from one extreme to the other.

When the expression controlling lever 10 —34— is set to produce an expression below fortissimo, and it is desired to accent any individual note or chord, the operator simply places the finger upon and depresses the accenting button or rod —57—, thereby 15 opening the valve —55— and connecting the chamber —48— with atmosphere, which causes the operation of the pneumatic —47— to actuate the valve —46— and connect the chamber —44— with the pneumatic —21— 20 through the conduit —40—. This causes a partial vacuum in and collapses the pneumatic 21— to unseat the valve —26—, and thereby establish direct communication between the exhaust device and key action so 25 that the full force of the exhaust device is felt upon the key striking pneumatics at the instant that the accenting button —57— is depressed.

Reference is hereby made to my pending 30 application No. 780,350 filed July 21, 1913, in which resistance pneumatics of graded sizes are specifically claimed.

Having thus described my invention what I claim and desire to secure by Letters 35 Patent is—

1. In a self-playing musical instrument, an expression-controlling mechanism includ-
40 ing an expression pneumatic and a plurality of separate resistance pneumatics, each hav-
ing separate connection with the first named pneumatic, in combination with an air ex-
haust device in communication with the first 45 named pneumatic, a valve actuated by the expression pneumatic to control such com-
munication means to connect each of the re-
sistance pneumatics to said exhaust device, 50 one at a time for producing a step-by-step gradation of expression, and manually con-
trolled pneumatic means for actuating said 55 valve independently of the expression pneu-
matic.

2. In a self-playing musical instrument, 55 the combination with an air-exhaust device and an exhaust-chamber of the playing ac-
tion, of an expression pneumatic in the con-
nection between the exhaust-device and said 60 chamber, an accenting pneumatic within and actuated by the expression pneumatic, a series of separate pneumatics adapted to re-
sist the collapse of the first named pneu-
matic, means for placing said separate pneu-
matics, one by one, in communication with 65 the exhaust device, and separate actuating means for the accenting pneumatic.

3. In a self-playing musical instrument,

the combination with an air exhaust device and an exhaust chamber in communication therewith, of separately operable pneumatics one within the other, and actuated by the suction from the exhaust device to 70 control such communication, a series of separate pneumatics adapted to resist the action of one of the first named pneumatics, and additional means for placing said separate pneumatics in communication, one by one, 75 with the exhaust device.

4. In a self-playing musical instrument, separately operable expression governing pneumatics, one within the other, and an exhaust device in communication therewith, in 80 combination with separate resistance devices connected to one of said pneumatics to oppose its collapse.

5. In a self-playing musical instrument, separately operable expression governing 85 pneumatics, one within the other, and an exhaust device in communication therewith, in combination with separate pneumatics connected to the outer pneumatic to oppose its collapse, and means to deflate said 90 separate pneumatics individually and collectively.

6. In a self-playing musical instrument, separately operable expression pneumatics, one within the other, and an exhaust device 95 in communication therewith, in combination with means to introduce varying degrees of resistance to the collapse of the outer pneumatic.

7. In a self-playing musical instrument, 100 separately operable expression pneumatics one within the other, and an exhaust device in communication therewith, in combination with a series of devices of substantially the same resisting power connected to one of said pneumatics to oppose its collapse, and means to make and break the resisting power of each device.

8. In a self-playing musical instrument, 110 separately operable expression governing pneumatics one within the other and an exhaust device in communication with one of said pneumatics, in combination with a series of separate pneumatics of substan- 115 tially the same size connected to one of the expression pneumatics to oppose its collapse, and means to deflate said separate pneumatics, one by one.

9. In a self-playing musical instrument, 120 separately operable governing pneumatics one within the other and an exhaust device in communication with the outer pneumatic, in combination with a series of separate pneumatics connected to the outer pneumatic to oppose its collapse and having a 125 combined area exposed to atmosphere sub-
stantially equal to that of the outer pneumatic, and means to deflate the separate pneumatics, one by one.

10. In a self-playing musical instrument, 130

the combination with an exhaust device, of separately operable expression governing pneumatics one within the other, the outer one being in communication with said device, an exhaust chamber of a playing action in communication with said outer pneumatic, separate pneumatics of substantially the same size connected to the outer pneumatic to oppose its collapse, and means to 10 place said separate pneumatics, one by one, in communication with said outer pneumatic.

11. In a pneumatic action for musical instruments, an exhaust device and action 15 having an exhaust chest in communication with the exhaust device in combination with means including a series of pneumatic resistance devices for effecting a step-by-step closing, and a step-by-step opening of 20 such communication, and an accenting pneumatic operable separately from said means.

12. In a pneumatic action for musical instruments, an exhaust device and action having an exhaust chest, a valved port connected to the exhaust device and chest, a 25 valve for said port, manually controlled pneumatic means to move the valve to its port with varying degrees of pressure, and an accenting pneumatic for opening said 30 valve independently of said pneumatic means.

13. In a pneumatic action for musical instruments, the combination with an exhaust device, of a pressure regulating pneumatic 35 in connection with the exhaust device, and a valve actuated by said pneumatic to partially close communication between the pressure regulating pneumatic and exhaust device and a separate valve controlling communication between the resistance pneumatics and exhaust device.

14. In a pneumatic action for musical instruments, the combination with an exhaust device, of a pressure regulating pneumatic 45 in communication with the exhaust device and including a valve for partially closing communication between the pressure regulating pneumatic and exhaust device, additional pneumatics connected to and controlling 50 the action of the pressure regulating pneumatic, and means for controlling the action of the additional pneumatics.

15. An expression regulating mechanism for self-playing musical instruments comprising a regulator acting under varying air tensions, separate devices for resisting such action in one direction, and means for operating said devices.

16. In a pneumatic action for musical instruments, the combination with an exhaust device and key action having an exhaust chest connected thereto, of means including two pneumatics one within the other for partially closing communication between the 65 exhaust device and chest to regulate the

expression, a plurality of resistance pneumatics communicating with the exhaust device and connected to one of the first named pneumatics to control its operation, additional means to cut off communication of one 70 or more of the resistance pneumatics with the exhaust device, and further means to actuate the inner pneumatic separately from the outer pneumatic.

17. In a pneumatic action for musical instruments, the combination with an exhaust device and key-action having an exhaust chest connected thereto, of means for partially closing communication between the exhaust device and chest to regulate the expression, a plurality of resistance pneumatics communicating with the exhaust device and connected to said means to control its operation, additional means to cut off communication of one or more of the pneumatics with the exhaust device, and separate means to actuate a part of the first named means to open full communication between the exhaust device and exhaust chest for accenting individual notes or 85 chords.

18. In a self-playing musical instrument, the combination with an exhaust device and a key-action having an air chest connected thereto, an expression pneumatic connected 95 to the exhaust device and to the air chest, a valve within and movable independently of the expression pneumatic for controlling communication between the exhaust device and air chest, separate pneumatics connected to and controlling the action of the expression pneumatic and also in communication with the exhaust device, means for cutting off communication of one or more of the separate pneumatics with the exhaust 105 device, and additional means for controlling the action of the valve independently of the separate pneumatics.

19. In a self-playing musical instrument, an expression regulator acting under varying air tensions, and means including separate pneumatics for applying different degrees of resistance to the movement of the regulator in one direction.

20. In a self-playing musical instrument, a wind inducing device and a communicating sound producing action, in combination with an expression regulator in the connection between said device and action, separate pneumatics and connections between 115 them and the regulator to resist the action of the regulator in one direction, and means for opening and closing communication between said pneumatics and wind inducing device.

21. In a pneumatic action for musical instruments, the combination with an exhaust device and an action chest communicating therewith, of an expression regulating mechanism comprising means to control 120

such communication including a lever and a finger controlled valve mounted on and movable independently of the lever.

22. In a self-playing musical instrument, 5 in combination with a wind inducing device and a communicating sound producing action, an expression regulator mechanism including an accenting valve, pneumatic means for actuating said valve, a lever and 10 finger controlled means on the lever for controlling the action of said pneumatic.

23. In a pneumatic action for musical instruments, the combination with a manual, 15 of an expression controlling mechanism including an accenting pneumatic and a manual mounted upon and movable independently of the former manual.

24. In a pneumatic action for musical instruments, the combination with a plurality 20 of separate manuals for different purposes, of an accenting pneumatic and means including finger pieces mounted upon said manuals and operable independently of each other and of their respective manuals for 25 operating the accenting pneumatic.

25. In a pneumatic action for musical instruments, the combination with an exhaust device and a pneumatic key action, of a valve controlling communication between 30 the exhaust device and key action, means including separate devices to resist the closing of the valve, means to control the action of said devices, and separate means to open said valve.

35. 26. In a mechanical musical instrument, the combination with wind-inducing devices and communicating sound producing devices, of tone-expression-controlling devices comprising a pneumatic regulator interposed 40 in and controlling the air passage between the wind-inducing devices and the sound-producing devices, a pneumatic actuator operative by atmospheric pressure and by the wind-inducing devices and adapted to operate 45 the regulator, and means adapted to connect the actuator with the wind-inducing devices to assure loud-tone effects or with the atmosphere to assure soft-tone effects.

27. In a mechanical musical instrument, 50 the combination with wind-inducing devices and communicating sound-producing devices, of tone-expression-controlling devices comprising a pneumatic regulator interposed in and controlling the air passage between 55 the wind-inducing devices and the sound-producing devices, a pneumatic actuator operative by atmospheric pressure and by the wind-inducing devices and adapted to operate the regulator, and a system of 60 passages and valves adapted to connect the actuator with the wind-inducing devices to assure loud-tone effects or with the atmosphere to assure soft-tone effects.

28. In a mechanical musical instrument, 65 the combination with exhaust-wind-inducing

devices and communicating sound-producing devices, of tone-expression-controlling devices comprising a pneumatic regulator interposed in and controlling the air passage between the wind-inducing devices and the sound-producing devices, a pneumatic actuator operative by atmospheric pressure and by the wind-inducing devices and adapted to operate the regulator, and means adapted to connect the actuator with the wind-inducing devices to assure loud-tone effects or with the atmosphere to assure soft-tone effects.

29. In a mechanical musical instrument, the combination with wind-inducing devices and communicating sound-producing devices, of tone-expression-controlling devices comprising a pneumatic regulator interposed in and controlling the air passage between the wind-inducing devices and the sound-producing devices, a pneumatic actuator operative by atmospheric pressure and by the wind-inducing devices and adapted to operate the regulator, and means adapted to connect the actuator with the wind-inducing devices to assure loud-tone effects or with the atmosphere to assure soft-tone effects; said regulator and actuator being relatively arranged to cause either of them to be operated directly from the other.

30. In a mechanical musical instrument, 95 the combination with wind-inducing devices and communicating sound-producing devices, of tone-expression-controlling devices comprising a pneumatic regulator interposed in and controlling the air passage 100 between the wind-inducing devices and the sound-producing devices, means such as a spring normally expanding the regulator to open said air-passage, a pneumatic actuator operative by atmospheric pressure and by 105 the wind-inducing devices and adapted to operate the regulator, and means adapted to connect the actuator either with the wind-inducing devices or with the atmosphere, whereby when the actuator is connected with 110 the wind-inducing devices the regulator will assure loud-tone effects and when the actuator is connected with the atmosphere the regulator will be more or less collapsed against the influence of its expanding means 115 to produce soft effects.

31. In a self-playing musical instrument, a pneumatic sound producing action and an exhaust device connected thereto, an expression pneumatic in the connection between 120 the exhaust device and action, a valve actuated by said pneumatic to regulate the air tension in the sound producing action, a resistance pneumatic arranged in opposition to the expression pneumatic to resist the collapse of the latter, means to control the action of the resistance pneumatic, and means for moving the valve independently of the expression pneumatic.

32. In a self-playing musical instrument, 130

an expression grading mechanism having a series of air ports, means including a lever for opening and closing said ports in succession, an accenting pneumatic, and means including an air port on the lever for controlling the operation of said accenting pneumatic.

33. In a self-playing musical instrument, a lever-controlled expression-grading de-

vice, the lever and an accent controlling device having an air-port on the lever.

In witness whereof I have hereunto set my hand this 19 day of August 1904.

LEWIS B. DOMAN.

Witnesses:

Mrs. THOMAS ELLIOTT,
NETTIE A. BIBBENS.
